[57] CLAIM

The ornamental design for handle for vegetation trimmer or similar article, substantially as shown and described.

DESCRIPTION

FIG. 1 is a front isometric view on a reduced scale showing my new design for handle for vegetation trimmer or similar article;

FIG. 2 is a rear isometric view thereof;

FIG. 3 is a front elevational view thereof;

FIG. 4 is a rear elevational view thereof;

FIG. 5 is a left side elevational view;

FIG. 6 is a right side elevational view;

FIG. 7 is a top plan view; and

FIG. 8 is a bottom plan view.

The invention is characterized by an upstanding portion with a transverse extension generally symmetrical about the upstanding portion; and by a bellmouth contour in the rearmost part of the invention.

FIG.1

FIG. 2.

FIG. 3

FIG. 4

FIG. 5
